BERNARD FERRAR, OF NEW YORK, N. Y.

SLIP-SHEETER

Application filed August 26, 1930. Serial No. 477,848.

This invention relates to stencil duplicators and has particular reference to attachments therefor known as slip-sheets.

The general object of the present invention is to provide an attachment of the character mentioned which is simple in construction, inexpensive to manufacture and reliable in operation.

Other objects and advantages of the invention will become apparent from the following description, taken in connection with the accompanying drawings in which—

Figure 1 is a plan view of a stencil duplicator and of the attachment embodying this invention; Figure 2 is a side elevation of the machine and attachment; Figure 3 is an end view of the attachment as seen from the left in Figures 1 and 2; Figure 4 is a vertical sectional view taken on line 4—4 of Figure 1 showing the relation of the oscillatory feeding shafts to a plurality of slip-sheets supported thereby; Figure 5 is a transverse sectional view of the feeding shafts, showing the relation of the same, when in normal position of rest, to the lowermost of a supported stack of slip-sheets; Figures 6 to 9, inclusive, are views similar to that of Figure 5, and showing the relation of the shafts at different stages to a slip-sheet undergoing ejection; and Figure 10 is a view also similar to that of Figure 5, and showing the relation of the slip-sheet to the shafts immediately subsequent to its release therefrom.

Referring to the drawings, the numeral 10 indicates a stencil duplicator of standard construction, having a frame, including side frame members 11, rotatably supported in the usual cylinder 12, beneath which the successive sheets of paper to be printed upon are successively fed from the feeding table 13, the printed sheets being ejected one by one from that end of the machine to which the slip-sheeter 15 embodying my invention is adapted to be attached.

The slip-sheeter includes a box-like receptacle or tray 16 having a bottom wall 17 and side walls 19, the bottom wall being provided with a notch 18. To the bottom wall 17, is suitably attached an arm 20, which extends an appreciable distance beyond one end of

the tray 16, the outer end of the arm 20 being provided with an upwardly curved end 21, which is adapted to be positioned beneath and engaging the transverse tie-rod 22 of the duplicator. When the arm 20 is positioned, as shown in Fig. 2, it serves to adequately support the slip-sheeter by reason of the fact that it engages the base 23 of the duplicator at a point intermediate the tray 16 and the tie-rod 22. In order that the slip-sheeter may be further secured to the duplicator or locked against displacement with respect to the same, there are provided a pair of locking fingers or arms 25, which are pivoted to the side walls 16 of the tray and are adapted to be moved down into engagement with the side frame members 11 of the duplicator, thereby exerting a thrust on the tray and forcing the arm 20 into firm engagement with the tie-rod 22 and the base 23 of the duplicator.

Arranged transversely of the tray 16, are a pair of bearing plates 26, which are secured respectively at opposite ends to the side walls 19. These bearing plates are located at the upper margins of the tray, so as to permit the printed sheets, as they are ejected from the duplicator, to enter the tray at one end and to permit such sheets to be removed from the tray at the other end thereof.

The ends of these bearing plates are so bent as to provide a plurality of upwardly projecting and parallel guide fingers 27, which extend longitudinally of the tray and are adapted to receive therebetween a plurality of slip-sheets 28 arranged in a stacked relation, as shown in Fig. 4.

Journalled in the bearing plates 26, are a pair of feeding or ejector shafts 30, which are located directly beneath the respective pairs of guide fingers 27 and extend longitudinally of the tray in a parallel relation to each other, such shafts serving to normally support the slip-sheets and to successively remove the lowermost of such sheets as the successive printing operations are carried out by the duplicator. Each of these shafts is milled longitudinally of its length to provide a groove 31 somewhat longer than the length of the respective slip-sheets, the walls 32 and

33 of such grooves serving, respectively, as ledges, for receiving the slip-sheet about to be ejected, and as abutments for removing or ejecting such sheet from the stack. As to the 5 abutments 33, it will be noted that they are radial with respect to the respective shafts, and that each of such abutments is of a width substantially equal to the thickness of the 10 respective slip-sheets. Concerning the ledges 32, it will be noted that they lie in planes which are off-center with regard to the respective shafts and are, respectively, perpendicular to the abutments.

Secured to the outer ends of the shafts 30, 15 are a pair of grooved pulleys 34 and 35, respectively. About the shafts 30 and adjacent the pulleys 34 and 35, are disposed a pair of coil or tortional springs 34' and 35', which are anchored to the adjacent bearing plate 26 20 and to the respective pulleys so as to normally maintain the shafts 30 in their respective positions shown in Fig. 4. The pulley 34 is provided on its outer face with a pair of bosses 37 and 38, which carry set screws 39, and are 25 formed with openings 40 leading into the peripheral groove of the pulley between the side flanges thereof. The pulley 35 is similarly provided with a boss 42, carrying a set screw 43, and formed with an opening 44, 30 leading into the peripheral groove of the pulley between the side flanges thereof.

A crank arm 45 is secured to the outer end 35 of a shaft 46, which is journalled in the side frame members 11 of the duplicator and is rotated through a train of gears, not shown, 40 operatively connected with the cylinder 12 in the usual manner. This crank arm is provided at its outer end with a pin or lug 47, adapted to detachably receive the hooked end 45 of a connector link 48, the opposite end of which link is secured to a flexible cable 50. This cable passes over a guide roller 51, journalled in a bracket 51', which is secured to one of the side walls 19 of the tray 16. From the guide roller 51, the cable 50 passes about 50 the pulley 34 in a clock-wise direction, as viewed in Fig. 3, and is secured to that pulley by the set screw 39 of the boss 37, into the passage 40 of which the end of the cable projects. Extending from the pulley 34 to the pulley 35, is a flexible cable 53, one end of which projects from the groove of the pulley 55 into the opening 40 of the boss 38, and the other end of which is passed about the pulley 35 in a counter clock-wise direction, as viewed in Fig. 3, and projects from the groove thereof into the opening 44 of the boss 42 where it is anchored by the set screw 43.

In order to prevent the sheets of paper, as 60 they are ejected from the duplicator, from being thrown under their own momentum through the tray 16, there is provided an abutment 56 at the rear of the tray. This abutment is substantially V-shaped, inverted, 65 and is formed intermediate the ends of a

length of wire which is so bent as to provide upwardly projecting arms 57 and 58 pivoted in the side walls 19 of the tray, the latter of which is provided with a downwardly depending finger 59 to which one end of a tension spring 60 is connected, the other end of such spring being connected to one of the side walls 19 of the tray near the bottom thereof. The spring 60 is sufficiently strong to hold the abutment 56 in its position shown 70 in Figs. 1 to 3, in which position it serves to limit the throw of the sheets as they enter the tray 16 from the duplicator, but is of such a nature that it permits the abutment to move rearwardly in advance of the sheets 75 as they are withdrawn from the tray, when they are gripped by one's hand, the fingers and thumb of which are readily accommodated, respectively, by the notch 18 formed in the bottom 19 of the tray and by the inverted V-shaped abutment 56.

In operation, the sheets to be printed upon are fed from the table 13 through the duplicator under the cylinder 12 thereof and are ejected one by one in printed form from the machine into the tray 16 of the slip-sheeter. As the drum 12 is rotated, the shaft 46 carrying the crank arm 45 is rotated in a properly timed relation to cause the slip-sheets to be successively removed from the bottom of the stack and forcibly impelled downwardly onto the printed sheets by the shafts 30 as such printed sheets are successively introduced into the tray 16 from the duplicator. The crank arm 45 in moving through 180° from its position, shown in Fig. 2, carries with it the cable 50, which, by reason of its connection with the pulley 34, causes that pulley—together with its shaft 30—to rotate in a counter-clockwise direction, as viewed in Fig. 3, the length of the arm being such with respect to the diameter of the pulley as to effect rotation of that pulley and that shaft through an arc of approximately 180°, as will appear from Figs. 11 to 10. As the pulley 34 is thus rotated, rotation of the pulley 35 is effected in a clock-wise direction, as viewed in Fig. 3, through the cable 53 which is connected to the pulley 34 and to the pulley 35, the extent of rotation of the pulley 35, together with its shaft 30, being the same as the pulley 34, together with its shaft 30. During such time as the crank arm 45 moves through the remaining 180° to its position shown in Fig. 2, the springs 34' and 35' act on the shafts 30 to return them to their normal positions, shown in Fig. 5. In rotating the shafts 30 from their position shown in Fig. 5 to their position shown in Fig. 9, the lowermost slip-sheet of the stack normally resting on the shafts 30, as shown in Fig. 5, assumes a position on the ledges 32, as shown in Fig. 6, as such ledges move under the longitudinal margins of the slip-sheet. Upon further ro-

tation of the shafts 30, the abutments 33 engage the longitudinal edges of the slip-sheet, as shown in Fig. 7, and thereafter move such sheet downwardly, as shown in Fig. 8, from the remaining slip-sheets, which are retained supported by the shafts 30 in the manner also shown in Fig. 8. As the slip-sheet is thus moved, it is caused to buckle downwardly along its longitudinal medial line, such buckling being effected by reason of the fact that the longitudinal edges are moved closer together by the abutments 33 of the rotating shafts. In buckling the slip-sheet, a certain amount of energy is stored therein, which energy is later utilized in a reactionary manner to impel the sheet downwardly when released from the shafts, as will hereinafter appear. In rotating the shafts 30 from their position shown in Fig. 8, each of the ledges 32 assumes an upwardly and inwardly inclined position with respect to the slip-sheet being ejected. As soon as the ledges 32 assume this position, the slip-sheet, due to its tendency to straighten out as a result of the energy stored therein during buckling, begins to react against the inclined ledges, and in doing so the slip-sheet slides downwardly along the inclined ledges, as shown in Fig. 9, to a point where it is released from the shafts and impelled forcibly on to the printed sheet last received from the duplicator by the tray 16. Following the ejection of the slip-sheet, the shafts 30 are returned to their normal positions, shown in Fig. 5, by the springs 34' and 35', preparatory to the next cycle of operation.

Although only one form of the invention is herein shown and described, it will be understood that various changes may be made without departing from the spirit of the invention or the scope of the following claims.

What is claimed is:

1. A slip-sheeter comprising a pair of rotatable members including sheet-supporting portions adapted to support a plurality of slip-sheets in a stacked relation, and including sheet-engaging means adapted to engage the lowermost of said sheets and forcibly remove it from its supported position while the remaining sheets are supported by said supporting portions.

2. A slip-sheeter comprising a pair of rotatable shafts each provided with a ledge adapted to normally support a plurality of slip-sheets in a stacked relation and each provided with an abutment adapted to engage the lowermost of said sheets and forcibly remove it from its supported position.

3. A slip-sheeter comprising a pair of rotatable shafts having portions adapted to normally support a plurality of slip-sheets in a stacked relation and having other portions adapted to engage and forcibly remove only the lowermost of said sheets and also portions adapted to move into supporting positions

beneath the remaining sheets and support them during the removal of said lowermost sheet.

4. A slip-sheeter comprising a pair of rotatable shafts having portions adapted to normally support a plurality of slip-sheets in a stacked relation and having other portions adapted to engage and forcibly remove only the lowermost of said sheets and also portions adapted to move into supporting positions beneath the remaining sheets and support them during the removal of said lowermost sheet, and means for rotating said shafts simultaneously in opposite directions.

5. A slip-sheeter comprising a pair of rotatable shafts each having a longitudinal groove, said grooves having ledges, upon which is adapted to normally rest the lowermost of a plurality of slip-sheets in stacked relation, and having abutment walls adapted to engage opposite edges of said lowermost sheet and cooperate with such sheet to forcibly remove it from its supported position, and having peripheral portions adapted to move beneath the marginal edges of the remaining sheets to support them during the removal of said lowermost sheet.

6. A slip-sheeter comprising means for supporting a plurality of slip sheets in a stacked relation, sheet-engaging means adapted to engage the opposite edges of the lowermost sheet, and means for relatively moving said sheet-engaging means toward each other while in engagement with said edges to effect a buckling of the lowermost sheet and to forcibly and completely remove it from its supported position.

7. A slip-sheeter for use with a duplicator and comprising means for supporting a plurality of slip-sheets in a stacked relation, sheet-engaging means adapted to engage opposite edges of the lowermost sheet and adapted to be moved relatively toward each other while in engagement with said edges to effect a buckling of the lowermost sheet and to forcibly and completely remove it from its supported position, and actuating means for effecting movement of said sheet-engaging means relatively toward each other.

8. In a slip-sheeter, supporting means for supporting a plurality of slip-sheets in a stacked relation, sheet-engaging means comprising a movable member adapted to engage an edge of the lowermost slip-sheet and move that edge toward the opposite edge of such sheet whereby such sheet is buckled and energy is stored therein, and means for utilizing such stored energy to release the sheet from said sheet-engaging means and impel it downwardly and out of contact with the remaining sheets.

In testimony whereof, I have signed this specification.

BERNARD FERRAR.
